ABSTRACT: Nb₃Sn superconductor material of increased critical current density is obtained by carrying out vapor deposition by decomposition of chlorides on a heated corrosion-resistant substrate in the presence of oxygen, for example 0.5 percent oxygen, in a mixed hydrogen and argon gas stream.

**PRODUCTION OF VAPOR-DEPOSITED Nb₃Sn
CONDUCTOR MATERIAL**

This invention relates to the production of Nb₃Sn Niobium-Tin superconductor material.

Niobium Tin of the formula Nb₃Sn is a superconductor with a high critical temperature (T_c=18.3° K.), which can sustain a very high critical current density (J_c ampa/cm²) before it loses its superconducting properties and becomes normal. It is thus a valuable material for the construction of superconducting solenoids, where it can be used at fields in excess of 100 k. gauss, but technological problems which arise from the brittle nature of Nb₃Sn make it difficult to work the material into suitable tapes and wires.

In one existing process for the fabrication of tape with Nb₃Sn layers supported by a metal substrate, Nb₃Sn is deposited from the vapor onto a substrate which is a corrosion-resistant alloy having a thermal-expansion coefficient similar to that of Nb₃Sn, for example on the material known under the Trade Mark Hastelloy. In this vapor-deposition process the substrate is a resistively heated to 800°-1000° C., and Nb₃Sn is deposited on the heated substrate by hydrogen reduction of the chlorides of niobium and tin, NbCl₄ and SnCl₄. The critical parameter of the niobium-tin deposit for use in solenoid winding is its critical current density, J_c, at a specified field. We have found that in general J_c has an optimum value in deposits formed at deposition temperatures around 800° C., and that its value will drop off in deposits formed at higher growth temperatures, while growth rates fall to impractically low levels when the substrate temperature is much below 700° C. In deposits formed at 800° C., typical values of J_c are 2-3×10⁴ a./cm.² at 4.2° K. in a field of 50 k. gauss, the current measurement being made with the magnetic field vector perpendicular to the current and parallel to the tape width. Some random variations in J_c are observed from sample to sample, and values of J_c as high as 5×10⁴ a./cm.² at 50 k. gauss have been observed.

The present invention has for an object to provide an improved vapor-deposition process for Nb₃Sn by which remarkably high and consistent J_c's can be obtained. According to the invention, oxygen is introduced into the gas stream used in the vapor-deposition.

While beneficial results have been observed within a range of 0.05 to 5 volume percent of oxygen in the gas stream, optimum results have been achieved with an oxygen concentration of about 0.5 volume percent. The substrate temperature is preferably kept at about 800° C., although the presence of the oxygen will show beneficial results within a temperature range of about 700° to 1,100° C., and in order to avoid excessive vapor condensation on the walls of the reaction vessel, it is preferred to use vapor temperatures which are not more than 100° C., below the substrate temperature.

In one series of experiments, as the oxygen concentration in the gas stream increased from 0.02-1 percent by volume, an almost linear increase in J_c was obtained, from 1.8×10⁴ to 4.2×10⁴ a./cm.², conditions being held constant.

Transmission electron-microscope work on vapor-deposited Nb₃Sn has shown that, while Nb₃Sn material as hitherto prepared generally consists of well defined and relatively perfect crystallites ranging from 0.2μ-0.3μ in diameter in some cases, up to 2μ-3μ in others, samples grown in the presence of oxygen in accordance with the invention showed additional diffraction contrast effects within the Nb₃Sn grains, fine lines and diffuse particles having been observed. It is thought that precipitation of a niobium-oxygen phase is taking place that these precipitates are acting as flux-priming centers, thus increasing critical current density.

EXAMPLE

In the best result obtained so far, a 6½μlayer of Nb₃Sn, grown on one-fourth-inch-wide Hastelloy maintained at 800° C., carried 400 a. at 46 k. gauss, a current density of 5.1×10⁴ a./cm.². Deposition was obtained with the flows in the gas stream, measured initially, as follows:

Hydrogen: 1,000 cc./minute

Argon: 1,350 cc./minute

NbCl₄: 125 cc./minute

SnCl₄: 45 cc./minute

Oxygen: 12½ cc./minute

What we claim is:

1. A method of depositing niobium-tin superconductor material on a substrate, which comprises heating the substrate to a temperature not substantially below 700° C., and not substantially higher than 1,000° C. and passing over the thus heated substrate a stream of gas including niobium chloride in the vapor state, tin chloride in the vapor state, hydrogen, and between 0.05 volume percent and 5 volume percent of oxygen.
2. A method as claimed in claim 1, wherein deposition is effected from a gas stream which contains 0.4 to 0.6 volume percent of oxygen.
3. A method as claimed in claim 2, wherein deposition is effected with the substrate maintained at approximately 800°C.
4. A method as claimed in claim 1, wherein the temperature of the gas stream is maintained above a minimum level that is 100°C. below the temperature of the substrate.
5. A method as claimed in claim 4, wherein deposition is effected with the substrate maintained at approximately 800°C.
6. A method as claimed in claim 5, wherein deposition is effected from a gas stream comprising approximately 39½ volume percent of hydrogen, 53 volume percent of argon, 5 volume percent of niobium chloride NbCl₄, 2 volume percent of tin chloride SnCl₄, and one-half volume percent of oxygen.
